HAIR WAVER

Fritz Binder, Kansas City, Mo.

Application July 17, 1933, Serial No. 680,806

9 Claims. (Cl. 132—33)

This invention relates to hair waving apparatus and particularly that member of such equipment upon which is wound strands of hair to be curled and which also supports the wound strand 5 of hair during the time heat is being applied thereto.

The primary object of this invention is the contemplation of an especially efficient, simple and durable part having members which insulate the 10 body of the apparatus from transmitting heat to the scalp and head and which maintain the spool receiving the strands of hair in a position against rotation until longitudinal movement is imparted thereto, such elements being constructed 15 in a special manner as will hereinafter be fully set forth.

With these general objects in view and such structural features as constitute minor objects in mind, the invention will be fully described by 20 reference to the accompanying drawing, wherein:

Figure 1 is a vertical, longitudinal, substantially central section through a hair waving unit embodying this invention.

Fig. 2 is a top plan view of the same, with 25 parts broken away for clearness.

Fig. 3 is an end elevation of the unit.

Fig. 4 is an end elevation of the unit illustrating the opposite end from that shown in Fig. 3, and,

Fig. 5 is a vertical, central cross section taken 30 on line V—V of Fig. 1.

Like reference characters will be used to designate similar parts throughout the several views, and the numeral 8 indicates a body formed of metal and having an upturned end portion 35 to form a bearing 10 at one end of body 8, and a bearing 12 at the other end thereof.

The base portion 14 of body 8 which extends between bearings 10 and 12 is both longitudinally and transversely arched as illustrated in Figs. 40 1 and 4 respectively. Since body 8 is made from sheet metal, it is preferable to blank the same in a manner which will permit forming base 14 from two thicknesses of the sheet metal from which body 8 is formed. In so forming the base 45 14 of body 8, laminations as shown in Fig. 1 assist in precluding any warping that might take place as the result of the application of heat when the hair curling unit is in operation. Each of bearings 10 and 12 respectively has a slot 16 and 18 respectively formed therein to receive 50 shafts 20 and 22 respectively in the manner hereinafter set down.

The curved face of base 14 lies adjacent the scalp when the hair is being curled and since 55 practice requires that heat be applied, this in-

vention has contemplated the use of an insulating face plate 24 which is made of fiber, wood, composition material, or any other substance which will suitably preclude transmission of heat to the scalp. The bearing face 26 of insulating 60 face plate 24 is likewise arched both longitudinally and transversely and this plate is held in operative position by a series of dove-tailed lugs 28 formed integrally, and removably projecting into grooves 30 formed in the lowermost lamination 65 of base 14.

As shown in Fig. 2, these grooves do not pass entirely across lowermost lamination of base 14 and therefore insulating face plate 24 may be moved into place from one side of base 14 only. 70 This manner of constructing and bringing together the parts not only precludes transverse sliding of plate 24, but permits blanking out and forming the body and slots 8 and 30 respectively in an economical manner.

As is shown in the drawing, and especially Fig. 1, plate 24 is held in spaced relation to the lowermost face of base 14. This air space 32 allows free circulation to break down any tendency of heat to pass from body 8 toward the scalp. 80 Spool 34 is pivotally mounted in bearings 10 and 12 respectively and the pintles 20 and 22 are formed in a manner to create a key 36 and head 38 respectively. A clamp 40, pivotally mounted as at 42, is utilized to retain the ends of 85 the strands of hair in place as spool 34 is being rotated, but since head 38 is squared, to be engaged by the two parallel sides of slot 18 formed by bearing 12, spool 34 must be held in a position where slot and head 18 and 38 respectively are 90 out of engagement before rotation can take place. The force holding spool 34 in a rotatable position must be sufficient to overcome the urge of spring 44 which establishes a constant pressure against spool 34 to move it against bearing 10 and to 95 hold head 38 in a locked position.

Spring 44 is wound about pintle 22 and extends against member 46 integral with pintle 22 and within spool 34. A complementary member 48 is rigidly secured in position within spool 34 and teeth 50 and 52 formed on members 46 and 48 respectively establish a ratchet whereby the spool may be moved in one direction only when head 38 is in the locked position within bearing 12. Obviously, this construction permits quickly 100 unwinding strands of hair when the time allowed for the application of heat has expired. A thimble 54 circumscribes spring 44 and extends into spool 34, as shown in Fig. 1, to not only house spring 44 along the portion thereof extending 105 110

from the end of spool 34 to bearing 12, but to safeguard strands of hair which may perchance fall over the end of the spool and otherwise be caught by this spring.

5 Spool 34 is tapered from its ends toward its center so that it is annularly, longitudinally arched and the distance between the arched upper face of base 14 and the outer face of spool 34 remains the same throughout the length of 10 the latter. This is an important feature and should be followed when constructing a unit of this character.

Strands of hair must be clamped securely against body 8 by some suitable means during 15 the use of this unit and to carry out this requirement, one edge of base 14 is provided with a resilient strip 56. Against this resilient strip 56 is swung a resilient clamping jaw 58 and the abutting, longitudinal, arched faces of members 20 56 and 58 are formed as shown in Fig. 5 to present longitudinal serrations or grooves which establish a much tighter connection between the two when the members are in the clamping position than would otherwise occur.

25 Member 58 is of rubber or other resilient material and is threaded upon a laminated strip 60, one end of which is hingedly mounted as at 62 to body 8. The other end of strip 60 is engaged by a clamping lock such as is well known in the 30 art and which comprises a link 64 and trigger 66, one end of which has a cam formed thereon to bear against the extended end of strip 60. This means of securing a clamping jaw in place is very well known in this art and further explanation is deemed unnecessary.

35 To preclude warping and to maintain the arched rigidity which is necessary, strip 60 is made of two pieces of material, one U-shaped in transverse cross section and the other embraced by said U-shaped member. These members 68 and 70 are clearly shown in Fig. 5.

The operation of this hair waving apparatus has been made clear during the course of the specification, and while many changes as to 45 specific structure might be made without departing from the spirit of the invention, it is desired to be limited only by the scope of the appended claims.

Having thus described the invention, what is 50 claimed as new and desired to be secured by Letters Patent is:

1. Hair waving apparatus comprising a spool-supporting body having a base and integral upturned ends forming bearings; and a spool, having 55 its annular side arched longitudinally, rotatably carried by the said bearings; said base being arched longitudinally and concentrically with the arched annular side of the spool whereby the distance between spool side and base remains the 60 same throughout the length of the spool as the latter is rotated upon its longitudinal axis.

2. Hair waving apparatus comprising a spool-supporting body having a base and integral upturned ends forming bearings; and a spool tapering from its ends toward its center rotatably carried by the said bearings, said base being longitudinally arched concentrically with the taper of

said spool and arched transversely whereby to form a concave outer face.

3. Hair waving apparatus comprising a spool-supporting body having a base and integral upturned ends forming bearings; a spool rotatably carried by the said bearings; and a resilient member interposed between one of said bearings and the adjacent end of the spool whereby to urge the said spool longitudinally toward the other bearing.

4. Hair waving apparatus comprising a spool-supporting body having a base and integral upturned ends forming bearings; a spool rotatably carried by the said bearings; pintles on the spool journaled in the bearings; a head formed on one of said pintles; and a resilient member interposed between one of said bearings and the adjacent end of the spool whereby to urge the said spool longitudinally toward the other bearing and to maintain the said head within the bearing adjacent the spring.

5. In a hair waving apparatus of the type described, a base; a hair receiving spool rotatably mounted on the base; and a longitudinally and transversely arched insulating face-plate supported in spaced relation to the said base.

6. In hair waving apparatus of the type described, a body formed of sheet metal and having upturned bearings and a base; an insulating face plate carried by the base in spaced relation thereto; and a spool rotatably mounted in the bearings, said base of the body being formed of two thicknesses of the sheet metal superimposed and arched both transversely and longitudinally.

7. In hair waving apparatus of the type described, a body formed of sheet metal and having upturned bearings and a base; an insulating face plate carried by the base in spaced relation thereto; and a spool rotatably mounted in the bearings, said base of the body being formed of two thicknesses of the sheet metal superimposed and arched both transversely and longitudinally, one of the thicknesses of the base having undercut notches formed therein, said face plate having 120 tongues formed thereon to enter said notches whereby the face plate is removably supported in assembled relation with the said body.

8. In hair waving apparatus of the type described, a longitudinally arched body having bearings formed thereon; a spool rotatably mounted in said bearings; a swingable clamping member on the body adapted to move to and from engagement with the body; and longitudinally serrated, resilient faces formed on the abutting edges of 130 the body and clamping member.

9. In hair waving apparatus of the type described, a body having bearings formed thereon; a spool having axial pintles rotatably mounted in said bearings; and a yieldable member between one of said bearings and the adjacent end of the spool, said member being a coil spring circumscribing one of said pintles and in engagement with the said bearing, said bearing having a thimble thereon, circumscribing the 140 spring and extending into said spool.
